US0D1019368S

(12) **United States Design Patent** (10) **Patent No.:** **US D1,019,368 S**
(45) **Date of Patent:** **** Mar. 26, 2024**

(54) **POSITIONING CLIP**

(71) Applicant: **Westlake Royal Stone LLC**, Houston, TX (US)

(72) Inventors: **Jeffrey D. Poirier**, Edmonds, WA (US); **Jakob W. H. Harris**, Kirkland, WA (US)

(73) Assignee: **Westlake Royal Stone, LLC**, Houston, TX (US)

(**) Term: **15 Years**

(21) Appl. No.: **29/756,242**

(22) Filed: **Oct. 27, 2020**

Related U.S. Application Data

(63) Continuation of application No. 29/659,835, filed on Aug. 13, 2018, now Pat. No. Des. 903,478.

(57) **CLAIM**

The ornamental design for a positioning clip, as shown as described.

DESCRIPTION

FIG. 1 is a front perspective view of a positioning clip showing our new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines in the drawings represent portions of the positioning clip and form no part of the claimed design.

1 Claim, 5 Drawing Sheets
